UNITED STATES PATENT OFFICE.

HENRY ALEXIS WILLIAMS, OF QUINCY, MASSACHUSETTS, ASSIGNOR TO THE PUTNAM NAIL COMPANY, OF BOSTON, MASSACHUSETTS.

MACHINE FOR FORGING HORSES-HOE-NAILS OR OTHER ARTICLES.

SPECIFICATION forming part of Letters Patent No. 625,229, dated May 16, 1899.

Application filed June 9, 1898. Serial No. 683,028. (No model.)

To all whom it may concern:

Be it known that I, HENRY ALEXIS WILLIAMS, a citizen of the United States, residing at Quincy, in the county of Norfolk and State 5 of Massachusetts, have invented certain Improvements in Machines for Forging Horseshoe-Nails or other Articles, of which the following is a specification.

My invention relates particularly to that 10 class of machines for forging horseshoe-nails and other articles in which the blank is cut from a coil of wire or a long strip or rod, then passed through a series of die-grooved rolls arranged in pairs at right angles to each other, 15 and subsequently finished to perfect the shape of the nail or other article produced. To improve the construction of machines of this character and enable them to perform their work more perfectly and effectively than heretofore is the object of my invention, which 20 consists in certain novel features, combination of parts, and details of construction, as will be hereinafter fully described, and specifically pointed out in the claims.

25 In the accompanying drawings, Figure 1 is a front elevation of my improved machine for forging horseshoe-nails and other articles. Fig. 2 is a side elevation of the same. Fig. 3 is a vertical section on the line 3 3 of Fig. 1. 30 Fig. 4 is an enlarged sectional plan on the line 4 4 of Fig. 1. Fig. 5 is a vertical section on the line 5 5 of Fig. 4. Fig. 6 is a horizontal section on the line 6 6 of Fig. 5. Fig. 7 is a vertical section similar to Fig. 5, with the 35 parts in a different position. Figs. 8 and 9 are enlarged sectional details of the dies for producing and finishing the scarf or bevel which forms the point of a horseshoe-nail.

Fig. 10 is a vertical section on the line 10 10 of Fig. 13. Fig. 11 is a sectional detail of the 40 spring which holds the blank after it has been severed from the rod and the parts adjacent thereto. Fig. 12 is an enlarged rear elevation of the upper portion of the machine, showing 45 the mechanism for feeding the rod or wire to the cutters. Fig. 13 is an enlarged horizontal section on the line 13 13 of Fig. 1. Fig. 14 is a vertical section on the line 14 14 of Fig. 4. Fig. 15 is a vertical section on the line 15 15 50 of Fig. 14. Fig. 15^a is a vertical section on the line 15^a 15^a of Fig. 1. Fig. 16 is a front

elevation of the movable portions of the scarfing, shearing, and compressing dies. Fig. 17 is a front elevation of the cylindrical bed or block which carries the stationary portions of 55 the scarfing, shearing, and compressing dies and the carrier-ring for receiving and carrying the nails to said dies. Fig. 18 is an enlarged vertical section on the line 18 18 of Fig. 2. Fig. 18^a is a horizontal section on the line 18^a 18^a of Fig. 18. Figs. 19, 20, 21, 22, 23, and 24 are sectional details of one pair of the die-grooved rolls, showing the cam-operated grippers which seize the blank and feed it to the said rolls, said grippers and rolls being shown 65 in different positions in said figures. Figs. 25 and 26 are perspective views of the dies for cutting the nail-blank from the coil of wire or rod. Fig. 27 is a detail of the mechanism which operates the cutters for severing the 70 blank from the wire or rod. Figs. 28, 29, 30, 31, 32, and 33 represent in front and side elevation the blank in different stages of completion. Fig. 34 represents in front and side elevation the finished nail after having been 75 trimmed and pointed. Fig. 35 represents the surplus portion of the nail sheared off by the cutting-dies in the operation of finishing the nail after passing through the rolls.

In the drawings, A represents the framework of the machine, of proper shape to support the working parts. B, Figs. 3 and 4, is the driving-shaft, to which is secured a bevel-gear C, meshing with and driving a horizontal bevel-gear D on a vertical shaft E, supported in bearings at the top and bottom of the framework and carrying at its upper smaller end a bevel-pinion 50, which meshes with a bevel-gear 51 on a horizontal shaft 52, supported in bearings rising from the top 80 plate a of the framework. The shaft 52 has secured to its outer end a crank-plate 53, Fig. 12, having a central longitudinal dovetail groove b, in which fits a crank pin or stud 54, made adjustable toward and from the center of said 85 plate 53 by means of a nut 55, said pin bearing against the under side of a feed-lever 56 which is held in contact with said pin by a spring 57, the revolution of the crank-plate 53 in connection with the spring 57 thus producing 90 an upward-and-downward movement of the lever 56, which through the medium of a 95

roller friction-clutch G transmits an intermittent rotary motion to a horizontal shaft 58, carrying a gear 59, which meshes with a gear 60 on a shaft 61, parallel with the shaft 58, these two shafts carrying at their outer ends a pair of grooved feed-wheels 62 and 63, between which passes the wire strip or nail-rod 48, and by which said rod is fed through a guide 49 into the path of the cutters, to be hereinafter described, which sever from said rod a short length of blank e, Figs. 10, 11, and 28, of the proper length for the horseshoe-nail to be forged, said nail rod or wire being straightened, if crooked, by passing between two grooved wheels 64 and 65 on one side and a single grooved wheel 66 midway between and opposite thereto, as shown in Fig. 1, the wheel 66 being made adjustable toward and from the wheels 64 and 65 by means of a screw 67. Between the outer bearings 70 and 71 of the feed-wheel shafts 58 and 61 is placed a spring 69, which tends to force them apart, and against the movable bearing 71 rests a pin 72, sliding in a tubular support 73, acted upon by a hand cam-lever 74, whereby the feed-wheels are caused to grip the nail-rod or be separated to release the same when required. By changing the position of the stud 54 in the groove b the throw of the roller-clutch feed-lever 56 may be varied to change the amount of movement of the feed-wheels and the consequent length of the nail-rod fed forward for a blank at each intermittent movement of said feed-wheels, and by the employment of a friction-roller feed-clutch for transmitting the movement of the lever 56 to the feed-wheels I am enabled to adjust the feed of the rod with the greatest nicety to produce a blank of the exact length required, which cannot always be accomplished with a ratchet-and-pawl mechanism, as with the latter no movement or feed can be effected less than the distance between two adjacent teeth of the ratchet-wheel.

75 76 are the cutters by which a piece of the nail-rod of the desired length to form a blank e, Fig. 28, is severed from the end of the nail-rod as the latter is moved forward by the feed-wheels. The upper cutter 75, which is stationary, is secured in a horizontal recess in a block f, bolted to the upper portion of the framework, and is made adjustable for wear by a screw 77, provided with a jam-nut 78. The lower or movable cutter 76 is adjustably secured to a horizontal slide 79, Figs. 1 and 10, movable in suitable bearings and having pivoted to its outer end a toggle 80, which is actuated to operate the cutter 76 by a bifurcated rod or pitman 81, Figs. 1 and 27, which is reciprocated by a cam 82 on a shaft 83, passing through a slot in the pitman 81, said cam being located between and acting upon two antifriction-rolls 84 85, placed between the forks of the pitman 81, whereby as the shaft 83 is rotated the desired movements are imparted to the cutter-slide 79. The cutters are so shaped as to cut off the two upper

corners of the blank, as shown in Fig. 28, as required to leave the head of the nail of the proper shape when finished.

70 86, Fig. 10, is a follower or plunger sliding in a horizontal recess in the block f and having its shank encircled between its head and the end of said recess by a spring 46, by which it is kept firmly in contact with the blank as the latter is being severed from the rod by the movable cutter, said blank being thus securely held in proper vertical position and prevented from turning or twisting while being cut, thereby causing the head to be cut 80 squarely and at right angles with the sides. The outer end of the shank of the follower 86, which projects through the block f, is provided with nuts 45, which act as a stop to limit the inward movement of the plunger and prevent it from projecting into the path of the nail-rod and obstructing the same. To prevent the blank from dropping through the conductor 87 onto the rolls beneath when the movable cutter has reached the end of its 90 backward movement, I provide a light spring 88, Figs. 10 and 11, which is secured to a covering-plate 40, Fig. 11, bolted to the block f, said spring extending up into a recess 90 in the outer end of the follower 86 and normally 95 projecting beyond the end of said follower into the path of the nail-rod, which forces it back into the recess 90 as it is fed down by the wheels 62 63. The spring 88 thus exerts a constant pressure on the blank and keeps 100 it firmly in contact with the end of the movable cutter 76 after the latter has been completely withdrawn, thus preventing the blank from falling by its own weight, which it is desired to avoid. The blank is pushed down 105 against the friction of the spring 88 and delivered positively into the first or upper conductor 87 by the next advance of the nail-rod, the blank thence passing head portion foremost directly into contact with the first of a 110 series of pairs of rolls H, provided with dies g, which act successively on opposite sides of the blank to gradually reduce the same and give it the proper shape, width, and thickness for a perfect horseshoe-nail, as shown 115 in Figs. 28 to 32, inclusive, the point being formed and finished after the nail has left the rolls by other mechanism, which will be hereinafter described.

120 The rolls H are arranged in pairs beneath each other, the two rolls of a pair being connected to revolve together by gears h, and each pair being placed at right angles to the pair immediately above it, as shown. The rolls are supported in boxes 91, Fig. 18, 125 mounted in housings I, each of which is adjustably secured to the vertical wall of the framework A by a heavy screw-bolt 92, Fig. 3, passing through a horizontal slot 93. The journal of one roll of each pair is elongated 130 and connected with a shaft 94 in line therewith by means of a coupling 95, Figs. 1 and 2, which permits the housing I to be adjusted when desired, and each of said shafts 94 is

provided with a gear 96, through the hub of which it slides with a spline. Each gear 96 meshes with and is driven by a gear 97, secured to a short shaft 98, supported in boxes 5 on the opposite side of the wall of the framework, as shown in Fig. 3, said short shafts 98 each carrying a bevel-gear 99, which meshes with and is driven by a bevel-gear 100 on the vertical shaft E, which is connected with the 10 driving-shaft, as previously described, motion being in this manner transmitted from the driving-shaft to each pair of die-grooved rolls H.

Suitable openings are cut through the walls 15 of the framework A to allow the gears 96 and 97 to engage each other. The boxes 91, which support the journals of each pair of rolls H, slide in suitable guideways in the housings I, and are held in place by a screw 101, bearing 20 against the outer box.

The blank comes into contact with the first or upper pair of rolls in an edgewise position, as shown in Figs. 19 to 24, inclusive, the dies acting on the edges of the blank and 25 causing it to be slightly reduced and drawn out, as shown in Fig. 29. The second pair of rolls, owing to their position at right angles to the pair above, act on the flat sides of the nail-blank, still further drawing and elongating it, as shown in Fig. 30. The third 30 pair again act on the edges of the blank, reducing and elongating it, as shown in Fig. 31, and the fourth pair act again on the flat sides of the blank to still further reduce it and 35 give it the proper shape, width, and thickness for a finished nail, Fig. 32, and in case the number of pairs of rolls should be increased they would be arranged to act alternately on the edges and flat sides of the 40 blank in the same manner. As soon as the blank has dropped through the first conductor 87 onto the first pair of rolls H it is seized by a pair of spring-grippers 102 similar to those shown enlarged in detail in Figs. 19 to 45 24, inclusive, which illustrate the third of the series of pairs of die-grooved rolls H and the grippers and gripper-operating mechanism connected therewith. Each pair of rolls is 50 provided with a pair of these spring-grippers 102, the upper ends of which are drawn toward each other by a light spring α^2 , Fig. 18, and as they are all of the same construction and are operated in the same manner by similar mechanism a description of one will apply to all. 55 The two members of these grippers, which are composed of spring metal, are pivoted at or near the center to a sleeve 103, which slides on the guide-tube or conductor 87 and is moved vertically thereon by an arm 105, secured to 60 a horizontal rock-shaft 106, having its bearings in the housings I, said shaft 106 carrying at its outer end an arm 107, Figs. 1 and 2, provided at its lower end with a projecting pin 108, which is engaged by a cam-groove 109 65 in a wheel 110, Figs. 1, 2, 3, and 18, secured to the end of the journal of one of the die-grooved rolls H. As soon as the blank drops

onto the rolls the portion *i* of the cam-groove 109, Fig. 2, acting on the pin 108, produces a slight descent or primary movement of the 70 sleeve 103, which causes the inclined projections 112 at the upper ends of the two members of the grippers to ride over the beveled projections or cams 113 on the guide-tube 87 and pass down onto the vertical portions of 75 said cams below the shoulders, as shown in Fig. 22, which cause the jaws of the grippers to tightly grasp the blank which is then held stationary with its head portion in contact with the rolls, as shown in Figs. 21 and 22, 80 while the pin 108 is passing through the concentric portion *k* of the cam-groove 109, during which time the recesses 115 of the dies *g* are being brought around into a position to receive the end of the blank to form the head 85 of a nail. The moment that these recesses 115 reach the end of the blank the portion 39 of the cam-groove 109, acting on the pin 108, will, through the connections described, produce a still further descent of the grippers, 90 which are in this manner caused to carry the blank down positively into the said recesses 115, as shown in Figs. 23 and 24, with a speed corresponding exactly to the surface velocity of the dies, whereby the nail-blank is always 95 properly placed within the die-grooved rolls to insure their acting on the blank at the right moment as they revolve in order to produce a nail of perfect shape. Were it not for this device the rolls if revolving at a high 100 speed might fail to take the blank at the right moment and it would consequently be crushed out of shape and spoiled. As the rolls continue to revolve from the position shown in 105 Figs. 23 and 24 the blank will be drawn by the rolls from between the grippers, which are then carried back to their normal position, (shown in Figs. 19 and 20) the nail-blank being at the same time by the movement of the rolls delivered into the next conductor 87, from 110 which it passes to the next pair of rolls H beneath, which draw down and elongate the blank still further, and so on throughout the 115 entire series.

As the mechanism which closes the spring-grippers tightly onto the blank and produces the descent of the same receives its motion from a cam-wheel secured directly to the journal of one of the pairs of rolls which is next to operate on the blank, it follows that the 120 movement of the die-grooved rolls and the grippers which coöperate therewith will be always synchronous, as required to produce perfect results.

The die-grooves of the several pairs of rolls 125 decrease in width and depth and increase in length as the pairs of rolls succeed each other in a downward direction, whereby the blank is reduced in width and thickness and drawn out until it is given the elongated shape shown 130 in Fig. 32.

To prevent breakage or injury to the machine by reason of a partially-completed nail becoming lodged in the conducting-tube 87,

which would cause those immediately following it to become jammed or wedged into said tube before the machine could be stopped by hand, I provide an automatic stop mechanism adapted to be operated by the rocking of the nail-conducting tube to one side on a pivot, which movement of the conducting-tube is effected by the descent therein of a nail-blank immediately following one lodged 5 in the tube, and thereby clogging the same, the second nail being carried by the rolls into contact with the first one and by its pressure thereon forcing the tube slightly to one side on its pivot, as will now be described.

10 15 The tube or conductor 87 beneath the lowest or fourth pair of die-grooved rolls is provided on one side with a lug 116, which is firmly, but removably, secured by a bolt and nut 117 to a plate 118 of the form shown in 20 25 30 Figs. 18 and 18^a, said plate being pivoted at 119 to the adjacent housing I. The tube 87 is by this construction capable of a slight movement to the right in the arc of a circle having its center at the pivotal point 119 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

K is a disk keyed to the driving-shaft B, 65 as shown in Figs. 14 and 15, and lying closely against the hub 148 of the driving-pulley L, which is free to turn on the shaft B when not

connected therewith by a pin 149, sliding in the disk K and adapted to enter one of a pair of recesses 150 in the hub 148, a flat curved 70 spring 151, secured to the disk K, acting on a projection at the outer end of the pin 149 to force the latter into the recess 150, and thus lock said disk to the hub 148, whereby motion is communicated to the driving-shaft. 75 The pin 149 is provided with a rectangular head 152, which lies in the path of the curved wedge-piece m when the latter is forced inward by the action of the spring 145, the end of the wedge-shaped piece then passing between the head 152 and the face of the disk K and forcing the pin 149 outward to withdraw it from the recess 150, when the driving-wheel will be disengaged from the driving-shaft B, thus instantly stopping the machine. 80 85 The release of the rod 140 is effected by the swinging to the right of the conducting-tube 87 when obstructed, as before described, which acts on the finger 38, and through the connections described releases the drop-lever 130, 90 the fall of which lifts the latch 134, when the rod 140 and wedge-piece m will be forced inward by the spring 145, causing the disk K on the driving-shaft to be unlocked from the hub of the driving-pulley L, as before described. 95 After the tube 87 has been cleared of the obstruction which produces the operation of the stop-motion, as above described, the rod 140 and wedge-piece m are drawn back by the hand-lever 137 until the latch 136 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

In the machine here represented I have shown the above-described stop-motion applied to the conducting-tube 87 of one pair of rolls H only; but in practice I prefer to pivot 110 each of the conducting-tubes 87 and provide similar means whereby the swinging of any one of said tubes 87 will effect the release of the drop-lever 130.

If the coil of wire or rod 48 should run out 115 without being noticed by the attendant, the last piece of the rod would be of greater length than required for a blank, and would consequently obstruct the rolls and cause injury or breakage. I therefore provide a stop- 120 motion to automatically arrest the feed when the nail-rod has nearly run out, as will now be described.

p is a horizontal bar sliding in an opening 154, Fig. 13, in a piece 155 and encircled 125 therein by a spring 156, bearing against a shoulder on the bar and the shouldered end of the opening 154, whereby an antifriction-roll 157, carried by one end of said bar p, is caused to bear lightly against the nail-rod, which 130 holds the bar p back against the resistance of the spring 156, as shown in Figs. 1 and 13, said spring serving to throw the bar outward as far as permitted by a stop-collar q as soon

as the end of the nail-rod has been carried below the roll 157. r is an upright arm which is pivoted at its lower end to the top plate a , as shown in Fig. 3, and has pivoted 5 to its upper end a long bar 160, having a notch 161, which engages the upper edge of a stationary plate 36, whereby the arm r is held back in the position shown in Fig. 3 against the resistance of a spring 162. The bar p is provided at the end opposite to that which carries 10 the roll 157 with an upward incline or wedge 163, Fig. 1, which when said bar p is thrown forward by its spring 166 on the running out of the nail-rod acts on the bar 160 and raises 15 it sufficiently to disengage its notch 161 from the plate 36, when the spring 162 will carry the top of the arm r into a position beneath the feed-lever 56 when the latter is raised, as shown in Fig. 12, thus intercepting said lever 20 and preventing any further movement of the feed-wheels 62, 63, as desired. The waste-piece or end of the nail-rod can now be withdrawn and a new rod inserted after the bar p has been drawn back in order to place its roll 157 25 against said new nail-rod, after which the bar 160 is drawn forward by taking hold of its outer end until its notch 161 engages the upper edge of the plate 36, when the machine will be again ready to continue its operation. 30 This stop mechanism will be found extremely convenient whenever it is desired to temporarily arrest the feed of the nail-rod without stopping the machine, it being merely necessary to lift the outer end of the bar 160 to dis- 35 engage it from the plate 36, when the spring 162 will carry the arm r into a position to intercept the feed-lever, as previously described.

After passing through the last pair of die-grooved rolls the partially-finished nail drops 40 headforemost into one of two pockets s , Figs. 2 and 5, extending diametrically through a rotary inverting carrier-wheel M , which is then turned one-half a revolution to deliver the nail-point foremost into one of the peripheral notches or sockets of a revolving nail-carrier Q , to be hereinafter described. The wheel M is secured to the end of a horizontal shaft 164, Fig. 15^a, supported in a long stationary bearing 165, to the outer end of 45 which is secured a curved guard-plate 166, partially encircling the periphery of the wheel M and serving to prevent the nail from dropping out of the pocket before the wheel has completed its half-revolution. The two pockets s for the nails are placed side by side, with their open ends on opposite sides of the periphery of the wheel, said pockets having a removable cover 167, whereby access may be gained thereto. The wheel is rotated intermittently in one direction one-half revolution 50 at a time by means of a ratchet-and-pawl mechanism 168, connected with a pinion 169^a on the shaft 164, which meshes with a rack 169, Fig. 15^a, on one side of a flat bar or pitman 170, Figs. 1 and 15^a, the upper end of which is slotted and embraces the adjacent shaft 94, the latter being provided with a cam

171, which acts on a cam-roll 172 on the bar 170, thus depressing the same against the resistance of a retracting-spring 173, Fig. 1, a vertical reciprocating movement being thus given to the bar 170 to produce through the connections described the desired movement of the carrier-wheel M , each half-revolution of which brings the open end or mouth of one 75 of the pockets s into a position to receive a nail from the die-rolls H above and the open end of the other pocket into a position to discharge the nail previously dropped therein into the rotary carrier-ring Q , by which it is 80 brought into a position to be acted upon by the scarfing, trimming, and compressing dies, which form the scarf or bevel at the point of the nail and trim or shear off the surplus metal to produce a perfect point and compress and finish the nail, as will be hereinafter described. The shaft 164 of the carrier-wheel M is provided with a friction-brake 174, Fig. 1, which prevents the wheel from being carried by its own momentum beyond the distance required to bring the mouth of each 85 pocket s directly beneath the conductor 87. N is a cylindrical bed or support bolted to the base of the machine, and Q is the intermittently-rotating nail-carrying ring, which 90 rests on the top of the cylinder N , said ring being provided around its rim or periphery with a series of vertical grooves or sockets t for the reception of the nails as they fall from the inverting carrier-wheel M , said nails being 95 suspended by their heads with their shanks hanging down outside the cylinder N , as shown in Figs. 5 and 17, and being carried around by the carrier-ring Q , to be successively acted upon by the scarfing, trimming, 100 and compressing dies. The carrier-ring Q is intermittently rotated by means of a reciprocating pawl 176, Figs. 1 and 2, which engages the crown ratchet-teeth 177 on said ring. This pawl, which is kept in contact with the 105 ratchet-teeth by a spring 178, is pivoted to an arm 179, secured to one end of a short shaft supported in a bearing 180 and having secured to its opposite end an arm 181, which is vibrated by a rod 182, pivoted thereto and 110 carrying at its upper end a strap encircling an eccentric 183 on the lower shaft 94, each revolution of which thus produces a movement of the carrier-ring Q equal to the distance between two adjacent nails in the sockets t . As the ring Q revolves each nail is 115 brought in succession into line with a reciprocating die 184, having its face inclined in both directions toward the center, forming a sharp horizontal edge 185, as shown in Fig. 120 8. This die 184 co-operates with a stationary member or anvil 186, adjustably secured within the solid portion a' of the cylinder N , as shown in Fig. 6, and serves to form the scarf or bevel at the point of the nail, as shown in 125 Fig. 8. The die 184 is adjustably secured by means of a screw 187 within a slide T , moving in a suitable guideway 188 and reciprocated by means of a toggle 189, to which is 130

pivoted a slotted bar 190, which is reciprocated by a cam 191 on a short shaft 192, supported in bearings 193 and having secured to one end a bevel-gear 194, Fig. 4, which meshes 5 with a bevel-gear 195 on the driving-shaft B, the bar 190 being provided with antifriction-rolls b' on each side of the cam 191.

U represents the reciprocating cutting or trimming die, which is secured to the slide 10 T, and 196 is the stationary punch, which operates therewith, said punch having the shape or outline of the flat side of a finished nail and being adjustable within the portion a' of the cylinder N by means of screws and 15 nuts, as shown in Figs. 5 and 6, whereby it may be adjusted for wear. The movable cutting-die U is composed of two portions, as shown in Fig. 6, the two cutting edges 198 of which are inclined downward and inward, as 20 shown in Fig. 5, thereby producing with the stationary punch 196 a shearing cut to trim off the surplus metal from the nail after the latter has been acted upon by the rolls, as 25 previously described, the piece of metal cut off from the lower portion of the shank being shown in Fig. 35, leaving the shank of the exact shape required for a perfect nail, as shown in Fig. 34.

Between the two side pieces of the cutting-die U is placed a slide 200, which has the 30 same shape or outline in cross-section as the punch 196, as shown in Fig. 16; but instead of having a straight vertical face it is inclined or curved backward and upward, as shown in 35 Fig. 5, to conform exactly to the shape of the inclined side of a horsehoe-nail. This slide 200, which forms the yielding back of a compressing-die—the punch forming the other member—is secured by a bolt within a slot in 40 the head of a spindle which slides horizontally in a support 204, made adjustable horizontally within the slide T by means of screws projecting from said support and having their heads in contact with the rear wall of the 45 opening in the slide T, which forms a stop therefor, whereby it may be caused to project more or less on the side next to the head 202. The spindle 203 is encircled within the support 204 by a stiff spiral spring 206, which 50 is confined between a shoulder at the inner end of the aperture in which it is placed and a shoulder on the spindle, said spindle being held in place when adjusted by nuts 207 on its threaded end, as shown in Fig. 6, a space 55 being left between the head of the spindle and the front end of the support 204 to permit the spindle to be forced backward against the resistance of the spring while the nail is being trimmed by the cutting-die U. Projecting 60 from the slide T on the side of the cutting-die U opposite to that on which the scarfing-die 184 is located is a compressing-die W, having an incline 208 on the upper half of its end or face corresponding to the 65 shape of the scarf or bevel at the point of the nail, as shown in Fig. 9, said die co-operating with a stationary member or anvil 209, secured

opposite thereto in the solid portion a' of the cylinder N, whereby a final compression is given to the point of the nail to give its bevel 70 a perfect finish. The anvil 209 is secured in its recess by a set-screw 210, Fig. 6. As the carrier-ring Q is rotated each nail suspended in one of its sockets t, as shown in Fig. 17, is brought into a position between the anvil 186 75 and the die 184, which is then advanced by the forward movement of the slide T to form the scarf or bevel at the point of the nail. The die 184 is then withdrawn and at the succeeding movement of the carrier-ring Q the 80 nail is brought into line with the cutting-die U and punch 196, the nail in the next notch or socket t of the carrier-ring Q being by the same movement brought into line with the scarfing-die 184. The cutting-die U then advances, when the rearwardly-yielding slide 200, which forms the back of the compressing-die, will force the nail against the punch 196, between which and the said yielding slide 200 it is then tightly compressed as said slide and 90 the cutting-die advance, the slide yielding against the resistance of the spring 206, previously referred to, which by its stiffness causes a considerable pressure to be exerted on the nail to hold it firmly and securely in place and 95 prevent any possibility of its turning or getting out of position while being cut or trimmed. As the cutting-die U continues to advance the lower portion of the shank of the nail is brought against its cutting edges, whereby the 100 piece of surplus metal shown in Fig. 35 is sheared off, the sliding back 200 still yielding against the resistance of the spring 206 until the head 202 of the spindle 203, which forms a stop, is brought into contact with the inner 105 edge of the support 204, when the farther advance of the slide T to the end of its forward movement causes the nail to be subjected to a very heavy pressure between the end of the slide 200 and the stationary punch 196, whereby the nail is given the proper shape for driving. The slide T, with the scarfing-die 184 and cutting-die U, is now drawn back to release the nail, which on the next movement of the carrier-ring Q is brought into line with 110 the compressing-die W and its anvil 209, between which on the next advance of the slide T the scarf is given a final squeeze to perfect the bevel at the point of the nail, the preceding nail being at the same time trimmed and the one directly in the rear of that compressed at the point to form the bevel or scarf, as 115 previously described. It will be understood from the forging that each intermittent movement of the carrier-ring Q brings one nail into 120 position to have the scarf or bevel at the point formed by the die 184, another nail into a position to be trimmed, and a third nail into position for receiving a final compression of the beveled point to harden the same, and 125 that three nails while suspended in the notches or sockets of the carrier-ring Q are simultaneously operated upon in this manner at each forward movement of the slide T, 130

thereby enabling the machine to perform its work in a rapid, effective, and economical manner. After the nails have been completed as above described they are carried 5 around by the revolution of the carrier-ring Q between said ring and a curved guard 210, encircling a portion of the same, the shanks of the nails at the same time being brought into contact with a curved deflector 211, out- 10 side of which they travel and which gradually forces the nails outward until their heads are clear of the sockets *t* in the ring Q, when the nails will fall by their own weight out of the machine.

15 Although I have thus far described my improvements as applied to a machine for forging horseshoe-nails, it is obvious that the above-described machine may be used for forging a great variety of different articles by merely 20 changing the forms of the dies and making other slight and unimportant changes in the mechanism to adapt it for the special article to be forged.

What I claim as my invention, and desire 25 to secure by Letters Patent, is—

1. In a forging-machine, the combination with a pair of die-grooved rolls and a conducting-tube or guideway leading thereto, of a sleeve sliding on said conducting-tube, a 30 pair of grippers pivoted to said sleeve and adapted to seize the blank or article to be forged, stationary cams or shoulders on the conducting-tube acting on the grippers to cause the latter to seize the blank on the de- 35 scent of the sleeve, a cam secured directly to one of the rolls, and mechanism operated by said cam for actuating said sliding sleeve, whereby the grippers secured thereto are caused to descend positively with a speed cor- 40 responding to the surface velocity of the dies in the rolls, substantially as described.

2. In a forging-machine, the combination with a series of pairs of die-grooved rolls arranged to act successively and alternately 45 upon opposite sides of the blank or article to be forged, and a conducting-tube or guideway leading from one pair of rolls to the next pair beneath, of a sleeve sliding on said conducting-tube, a pair of grippers pivoted to 50 said sleeve and adapted to seize the blank within the conductor after it has dropped onto the rolls, stationary cams or beveled shoulders on the conducting-tube acting on the grippers to cause the latter to seize the blank on the descent of the sleeve, and means 55 for operating the sleeve to cause the grippers to descend with a speed corresponding to the surface velocity of the dies in the rolls, substantially as described.

60 3. In a forging-machine, the combination with the die-grooved rolls and the conducting-tube leading thereto, of a sleeve sliding on said conducting-tube, a pair of spring-shank grippers centrally pivoted to said sleeve and 65 having their jaws located within the conducting-tube and provided at their upper ends with projections, beveled shoulders or cams

on the conducting-tube adapted to act on the projections at the upper ends of the grippers to close their jaws upon the blank as they are 70 carried down with the sleeve, and means controlled by a cam secured directly to one of said die-grooved rolls for imparting a primary movement to the said sleeve and grippers to cause the latter to tightly grip the blank, and 75 a subsequent movement, following a rest, whereby the grippers are caused to positively carry down the blank with a speed corresponding to the surface velocity of the dies and 80 properly place said blank within the recesses of the dies, substantially as described.

4. In a forging-machine, the combination with the feed-wheels, and blank cutting and forging mechanism, of a spring-pressed sliding bar arranged at right angles to the rod 85 from which the blanks are to be cut, a stop-motion for arresting the movement of the feed-wheels only, without stopping the machine, and connecting mechanism between the stop-motion and the spring-pressed bar, 90 whereby the movement of the latter by reason of the rod passing out of contact therewith, will operate the stop-motion to arrest the feed, thereby leaving the rest of the machine in motion to finish the nails that are in 95 the different stages of completion, substantially as described.

5. In a forging-machine, the combination with the feed-wheels for feeding the nail-rod, and mechanism operated by a feed-lever for 100 intermittently actuating said feed-wheels and mechanism for operating said feed-lever, of an automatic stop-motion comprising a sliding bar adapted to be kept in contact by a spring with the nail-rod from which the 105 blank is to be cut, an arm adapted to intercept and arrest the movement of the feed-lever to disengage or disconnect it from its operating mechanism, and means whereby 110 said arm is moved to intercept the feed-lever when the sliding bar is released by the nail-rod passing out of contact therewith, substantially as described.

6. In a forging-machine, the combination with the feed-wheels for feeding the nail-rod 115 and mechanism operated by a feed-lever for intermittently actuating said feed-wheels, of an automatic stop-motion, comprising a sliding bar arranged at right angles to the nail-rod and provided with an antifriction-roll 120 kept in contact with the nail-rod by a spring acting on said sliding bar, a spring-pressed arm adapted to pass beneath the feed-lever to intercept the same and arrest its movement, and a bar pivoted to said spring- 125 pressed arm and provided with a notch for engaging the edge of a stationary plate, said sliding bar having an incline adapted to raise the notched bar and trip the same when said sliding bar is released by the nail-rod passing 130 out of contact therewith, substantially as described.

7. In a forging-machine, the combination with the feed-wheels and mechanism for in-

- termittently rotating the same, of a feed-lever for actuating said mechanism, a spring connected with said lever, means for raising said lever against the resistance of its spring, and an intercepting arm or lever adapted to be thrust beneath the feed-lever to intercept the same when raised and thereby arrest the movement of the feed-wheels without stopping the machine, substantially as described.
8. In a forging-machine, the combination with the feed-wheels and their shafts connected by gears, of the roller friction-clutch connected to one of said shafts, a feed-lever for operating said clutch, a spring connected with the feed-lever, a rotating crank-plate provided with an adjustable crank-pin or stud acting on the feed-lever to raise the same against the resistance of its spring, and a stop lever or arm adapted to be thrust beneath the feed-lever to intercept the same when raised and thereby arrest the movement of the feed-wheels without stopping the machine, substantially as described.
9. In a forging-machine, the combination with the stationary and movable cutters, of a spring placed opposite to the end of the movable cutter and normally projecting into the path of the blank cut from the rod, whereby said blank is supported until positively forced down by the next movement of the rod, substantially as described.
10. In a forging-machine, the combination with the feed-wheels and the stationary and movable cutters, of a spring-actuated follower arranged opposite to the end of the movable cutter and adapted to be kept in contact with the blank as it is being severed from the end of the rod, said follower being provided at its outer end with a recess, and a spring extending into said recess and adapted to normally project beyond the end of the follower into the path of the nail-rod to prevent the blank from dropping by its own weight after being severed from the rod, substantially as described.
11. In a forging-machine, the combination with a pair of die-grooved rolls, of a pivoted conducting tube or guide located beneath the same and movable laterally on its axis by the contact of a blank with an obstruction in said tube, and a stop-motion adapted to be tripped to stop the machine by the movement of said conducting-tube when obstructed, substantially as described.
12. In a forging-machine, the combination with a pair of die-grooved rolls, of a conducting-tube located beneath the same and pivoted on one side of its vertical axis, whereby it may be rocked laterally in the arc of a circle, a spring for keeping said tube in its normal position for receiving a blank from said rolls, a rock-shaft provided with an arm in contact with the movable conducting-tube, a second arm secured to said rock-shaft, and provided with a notch, a drop-lever engaged and supported by said notched arm and adapted to fall by its own weight when re-

leased by said notched arm, and means operated by said drop-lever for disengaging the driving-wheel from the driving-shaft, to stop the machine when the conducting-tube is obstructed, substantially as described.

13. In a forging-machine, the combination with the driving-shaft and the driving-wheel loose thereon, of a disk fast on said driving-shaft and provided with a spring-pressed locking-pin adapted to engage the hub of the driving-wheel, a spring-operated wedge adapted when released to withdraw the locking-pin from the driving-wheel, a hand-lever connected with said wedge, a latch for holding the wedge when drawn back by the hand-lever, a rod for lifting said latch, a drop-lever pivoted to said lifting-rod, a notched arm adapted to support the drop-lever, said arm being secured to a rock-shaft, an arm or finger on said rock-shaft, and a laterally-movable conducting-tube located beneath a pair of die-grooved rolls and adapted to move said finger to release the drop-lever and thereby effect the unlocking of the driving-shaft from the driving-wheel, substantially as described.

14. In a forging-machine, the combination with the intermittently-rotating carrier-ring provided around its periphery with sockets for holding the nails, of a die for forming a scarf or bevel at the point of the nail, a shearing and compressing die, and a die for producing a final compression of the point of the nail after being trimmed, the movable members of said dies being secured to a single reciprocating slide and arranged to operate simultaneously on a series of successive nails in different stages of completion while held in the sockets of the carrier-ring, and means for discharging said nail from the carrier-ring when completed, substantially as described.

15. In a forging-machine, the combination with the intermittently-rotating carrier-ring provided around its periphery with sockets for holding the nail, of the cylinder or bed N forming a support for said carrier-ring and having secured thereto the stationary members of a series of dies for successively beveling the point of the nail, shearing the same and subsequently giving it a final compression, the reciprocating slide carrying the movable members of said dies, and a yielding slide arranged between the two cutting edges of the movable shearing-die and forming the back of a compressing-die coöperating with the punch member of the shearing-die, said yielding back being provided with a spindle sliding within a support made adjustable within the reciprocating slide, and having a head forming a stop to arrest the rearward movement of the yielding back of the die, whereby the nail is subjected to a heavy pressure to give it the proper shape for driving, and a stiff spring encircling said spindle, all operating substantially as described.

16. In a forging-machine, the combination with the reciprocating slide T and means for operating the same, of the shearing-die U se-

cured to said reciprocating slide T and coöperating, with a stationary punch member, the support 204 made adjustable within the slide T by means of screws, the spindle 203 encircled by a spring and carrying a slide 200 arranged between the two cutting edges of the movable member of the shearing-die and forming the yielding back of the compressing-die, said spindle being provided with a head forming a stop to arrest the inward movement of the yielding back of the die, whereby the nail is subjected to a heavy pressure to give it the proper shape for driving, and a stiff spring encircling the spindle of the said yielding back to keep the same in contact with the nail while being sheared, substantially as described.

5 10 15

Witness my hand this 2d day of June, A. D. 1898.

HENRY ALEXIS WILLIAMS.

In presence of—

P. E. TESCHEMACHER,
LOUISE A. CHACE.
